(57) **CLAIM**

The ornamental design for a VR controller grips cover set, as shown and described.

DESCRIPTION

FIG. 1 is a front, left and top perspective view of the right hand for a VR controller grips cover set, showing our design; FIG. 2 is a rear, right and top perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a cross-sectional view of the right hand of the VR controller grips cover set of FIG. 1, taken along section line 9-9 as depicted in FIG. 4; FIG. 10 is an enlarged view of detail 10 in FIG. 2; FIG. 11 is a front, left and top perspective view of the left hand of the VR controller grips cover set; FIG. 12 is a rear, right and top perspective view thereof; FIG. 13 is a front elevation view thereof; FIG. 14 is a rear elevation view thereof; FIG. 15 is a left side elevation view thereof; FIG. 16 is a right side elevation view thereof; FIG. 17 is a top plan elevation view thereof; FIG. 18 is a bottom plan elevation view thereof; FIG. 19 is a cross-sectional view of the left hand of the VR controller grips cover set, taken along section line 19-19 as depicted in FIG. 14; and, FIG. 20 is an enlarged view of detail 20 in FIG. 11. The broken lines depict portions of the VR controller grips cover set that form no part of the claimed design. The dot-dash broken lines in FIGS. 2, 10, 11, and 20 depict the boundaries of the enlargements that form no part of the claimed design.
